UNITED STATES PATENT OFFICE.

FREDERICK R. SUNDERMAN, OF NEWBURG, NEW YORK, ASSIGNOR TO SUNDERMAN CORPORATION, OF NEWBURG, NEW YORK, A CORPORATION OF NEW YORK.

JACK.

Application filed April 12, 1922. Serial No. 551,975.

To all whom it may concern:

Be it known that I, FREDERICK R. SUNDERMAN, a citizen of the United States, and resident of Newburg, in the county of 5 Orange and State of New York, have invented certain new and useful Improvements in Jacks, of which the following is a specification.

My invention relates to jacks, and more 10 particularly to hydraulic jacks. The invention is especially useful and adapted for jacks used as part of the equipment of automobile trucks and the like.

The object of the invention, generally 15 stated, is to provide a strong, durable and efficient jack which may be economically constructed.

In the preferred embodiment of the invention as shown, all of the parts, including 20 valves, are contained within the main shell of the device. The device is free of control valve handles projecting from the outside of the shell where they are apt to be damaged in the rough usage given jacks, and the 25 valves are controlled directly from the handle which in turn is located at the upper portion of the jack well above the ground.

The invention consists in the novel 30 features, arrangements, combinations and construction of parts hereinafter described according to the preferred embodiment of the invention, and the invention will be more particularly pointed out in the appended claims.

Further objects and advantages of the 35 invention will be more fully understood from the following description taken in connection with the accompanying drawings illustrating the preferred embodiment of the invention, in which:

Fig. 1 is a cross-section taken on the vertical center line of the jack; and

Fig. 2 is an enlarged view showing the valve ball mechanism.

Referring to the drawings, 1 is a base into 45 which is threaded a tube 2 which at its upper end is threaded into a housing or cap member 3. The tube 2 and the housing 3 together constitute the outer shell or wall of the reservoir for the fluid, such as oil. Within this reservoir is a ram element comprising a tube 4 the lower end of which is threaded into a valve-containing casting 5 which is cylindrical in outline to serve as a 50 piston member, and is cored out at its up-

per portion so as to provide an upwardly extending annular flange 6 the inner surface of which is threaded to receive the lower end of the tubular member 4. From the lower portion of this casting 5 there is a tubular 60 projection 7 the lower end of which is threaded to receive a cap 8, having a central opening 8'. Upon this lower projection 7 there are a plurality of piston packing members 9 and 10. The piston member 9 is preferably of leather or some suitable flexible or expansible material which will have a tight sliding fit with the inner wall of the reservoir chamber, while the second member 10 is preferably of metal and serves to hold 65 the flexible member 9, which is really the packing member, into position against the reservoir wall. This member 10 in turn is held in position tightly against the packing member 9 by means of the cap member 8 which is capable of threaded adjustment toward and away from the member 10 to adjust the force of the same against the packing member.

The casting 5 has a slight clearance with 70 the reservoir wall so that the only point of close contact is between the packing member and the wall of the reservoir. It will thus be noted that in operation the tubular reservoir member constitutes the cylinder in 75 which the piston member operates.

The casting 5 is in reality a valve chamber 80 and is provided with suitable ball check valves and passages for controlling the flow of fluid from above the piston member to below the same, and vice versa. The arrangement is as follows: The casting is provided with a horizontal cored out portion 11 extending to the center of the casting, and from thence to the opposite side of the casting and in alignment with the cored out portion 11 there is a restricted passage 12 the outer portion of which communicates with an annular groove 13 extending around the periphery of the casting, while the inner portion of the passage 12 is provided with a valve seat for the ball check valve 14. The bore 11 is provided with a threaded tap or plug 15, between the inner end of which and the ball there is provided a spring 16 to hold 90 the ball upon its seat. From the lower end of the casting there is a vertical bore 17 which communicates with the horizontal bore, and its upper portion is also provided with a valve seat for ball check valve 18. 100 105 110

Spring 19 positioned between this ball and the cap 8 serves to hold the ball against its seat. The ball 14, as will hereinafter be explained, controls the flow of fluid from the reservoir above the piston member to the interior of the valve chamber 5, while the ball 18 controls the flow of fluid from the interior of the valve chamber to the space below the piston member.

10 The tubular ram member 4 extends through the central portion of the reservoir cap member 3, the latter being provided with packing to form a tight joint around said member 4. This packing consists of a suitable packing ring or packing material 20 located in an annular recess at the upper part of the cap, and it is forced tightly against the outer wall of the tubular member 4 by a metal packing ring 21 which is threaded into the annular recess. This metal ring is beveled as shown so that when it is screwed in tightly it will force the packing toward the tubular member 4. The upper portion of the tubular member projecting beyond the packing is threaded on its outer surface to receive a load supporting cap member 22, and this cap member is cored out to provide a chamber 23 within which is slidably pivoted at 24 the pump lever 25. To this lever is pivoted at 26 a pump plunger 27 which has a pumping fit within the tubular member 4. The upper portion of ram member 4 is provided with an annular recess for receiving packing 28 held in position by a metal packing ring 29 which is threaded into this recess.

15 The lower end of the pump plunger 27 is provided with a small projection 30 which, in the normal pumping operation, does not reach the ball 14, but when the plunger is thrown in its lowermost position, as will hereinafter be explained, the projection 30 engages the ball 14 to dislodge it from its seat, and the ball 14 in turn engages ball 18 to dislodge it from its seat so as to provide for the return of the fluid from below the piston member to the reservoir above the same when lowering the jack.

20 The following provision is made for normally keeping the pump plunger from engaging the ball. The lever is provided with a suitable handle 31 slidably mounted thereon by any suitable means, such for example as by a pin 32 from the lever extending into a slot 33 in the handle or vice versa. This handle is provided at its upper end with a sleeve 34 which is adapted, at the down stroke of the lever during the pumping operation, to engage shoulder 35 on the supporting cap to limit the downward movement of the lever. But if the handle is pulled outwardly on the lever so as to remove the sleeve from alignment with the shoulder, then the lever may be given a further downward movement sufficient to

cause the lower projection 30 on the pump plunger 27 to engage the upper ball 14 and displace the balls from their seats as above mentioned, to permit the return of the oil from below the piston member to the reservoir above the same. The slideable handle may either form a snug sliding fit on the lever, or it may be held in its upper position by a suitable thumb-operated spring-pressed detent in the handle, of any well known construction for that purpose, or the handle may be provided with a spring which normally holds it in its upper position except when it is being pulled outwardly against the spring. These details are not shown, since they will be understood by those skilled in the art. In fact, any suitable arrangement on the lever may be provided which normally limits the downward stroke of the lever, and which may be manually shifted to permit the further movement. For example, the sleeve 34 may simply have its lower side extending further up on the lever 25 than the upper side, so that to get a further downward stroke the handle is simply given a twist on the lever to bring the short side of the sleeve to the lower position.

25 The operation of the embodiment of the invention described is as follows: As the lever is lifted from the position shown the plunger 27 is raised, producing a suction within the tubular ram member 4 which causes ball 14 to move from its seat against the spring and permits the oil to flow from the reservoir above the piston member along the clearance between the piston member 5 into the annular groove 13 through the bore 12 into the central part of the piston member or valve chamber and from thence through the opening 36 to the pump chamber. On the downward stroke the pressure in the pump chamber immediately causes the ball 14 to be seated and ball 18 to be dislodged from its seat, whereupon the oil or other fluid is forced past the ball 18 through the vertical bore 17, thence through the opening 8' to the space below the packing elements of the piston member, whereupon the tubular ram member 4 carrying the piston commences to rise. As soon as the pump plunger is lifted on the next up stroke, ball 18 is closed and ball 14 unseated, and so on. The jack will remain in the position to which it is operated at any point in its upward movement, and when it is desired to lower the jack it is only necessary to give the handle 31 the desired movement to move sleeve 34 away from projection 35, and then force the pump lever in its lowermost position against projection 35 to unseat the ball valves as aforesaid, and allow the fluid to flow from below the piston member of the ram to the oil reservoir above the same.

It will thus be observed that the preferred embodiment of the jack shown provides a readily and simply operated and controlled device all of the parts of which are controlled directly from the handle grip.

While I have described in detail the preferred embodiment of the invention, it will be obvious to those skilled in the art, after understanding the same, that various modifications in the arrangement and construction of the parts may be made without departing from the spirit or scope of my invention, and I aim to cover all such modifications in the appended claims.

15. What is claimed is:—

1. In a hydraulic jack, a movable piston, a ram carried by and movable with the piston, a pump movable with and with respect to the ram, the action of the pump being instrumental in moving said piston, and a reservoir into which the ram extends and against the wall of which the piston bears.

2. In a hydraulic jack, a movable piston, a ram carried by and movable with the piston, a reservoir into which the ram extends and against the wall of which the piston bears, said reservoir constituting the only reservoir within which liquid is contained, and a pump operable within the reservoir to raise and lower the piston.

3. In a hydraulic jack, a hollow ram, a piston operable to move the ram, a reservoir into which the ram extends and against the wall of which the piston bears, and a pump comprising a pump chamber formed by the hollow ram.

4. In a hydraulic jack, a movable piston, a hollow ram carried by and movable with the piston, a reservoir into which the ram extends and against the wall of which the piston bears, said reservoir constituting the only reservoir within which liquid is contained, and a pump operable to transfer the liquid from one to the other side of the piston, the relation of the pump to the ram being such that a pump chamber is formed by the hollow of the ram.

5. In a hydraulic jack, an upstanding cylindrical reservoir, said reservoir constituting the only reservoir within which liquid is contained, a piston movable within the reservoir, a ram carried by the piston and extended at one end without the reservoir, and a pump operable to transfer the liquid from one to the other side of the piston.

6. In a hydraulic jack, a reservoir containing liquid, a hollow ram, a piston operable within the reservoir to raise and lower the ram, and a pump plunger operable within the ram to transfer the liquid from one to the other side of the piston.

7. In a hydraulic jack, the combination of an upright cylindrical reservoir for fluid, a piston and a ram moved thereby, said reservoir serving as a cylinder for the co-oper-

ating piston, and valve mechanism carried by the ram and piston for controlling the flow of fluid from one side of the piston to the other within the reservoir.

8. In a hydraulic jack, the combination of an upright cylindrical reservoir for fluid, a piston and a ram moved thereby, said reservoir serving as a cylinder for the co-operating piston, a pump for pumping fluid from one side of the piston to the other within the reservoir, valve mechanism carried by the ram and piston for controlling the flow of fluid from one side of the piston to the other, and means controlling said valve mechanism from the pump to open the valves to permit the return of fluid from beneath the piston.

9. In a hydraulic jack, the combination of a reservoir, a ram, valve mechanism for admitting fluid from the reservoir to beneath the ram member and vice versa, a pump for pumping said fluid, and control means for opening the valves through movement of the pump to permit the lowering of the ram, said control means comprising a member on the pump lever movable with respect thereto.

10. In a hydraulic jack, the combination of a reservoir, a ram, valve mechanism for admitting fluid from the reservoir to beneath the ram member and vice versa, a pump for pumping said fluid, and control means for opening the valves through movement of the pump to permit the lowering of the ram, said control means comprising a member movable with respect to the pump lever for varying the stroke of the pump.

11. In a hydraulic jack, the combination of a reservoir, a ram, valve mechanism for admitting fluid from the reservoir to beneath the ram member and vice versa, a pump for pumping said fluid, and control means for opening the valves through movement of the pump to permit the lowering of the ram, said control means comprising a handle grip movable with respect to the pump lever for varying the movement of the pump plunger.

12. In a hydraulic jack, the combination of an upright reservoir, a hollow ram extending into the reservoir and carrying a piston member, its lower end containing a valve chamber, a load-supporting member at the upper end of the ram, a pump plunger operating within the hollow ram, and a pump lever mounted on said load-carrying member and connected to operate the plunger.

13. In a hydraulic jack, the combination of a cylindrical reservoir member secured to a base member, a reservoir chamber secured to the upper end of said cylindrical reservoir member, a hollow ram member extending into said reservoir, carrying at its lower end a detachable member, valve mechanism within

said detachable member, piston packing means secured to said detachable member, a pump plunger operating within said hollow ram member, and means carried at the upper 5 end of said ram member for operating said plunger.

14. In a hydraulic jack, a movable piston, a ram carried by said piston, a pump within said ram, and a reservoir into which said 10 ram extends.

15. In a hydraulic jack, a ram, a movable piston attached to and co-operating to raise said ram, a pump within said ram, a reservoir for storing fluid and lying wholly within 15 said ram, said piston being operable in said reservoir and said ram extending into said reservoir.

16. In a hydraulic jack, means constituting the outer wall of a reservoir, a ram 20 piston within said means and engaging the inner walls thereof, a ram extending into said means and secured to the piston and having an outer diameter such as to provide a space between it and said first means for 25 the fluid supply, and a pump movable with and with respect to the ram for transferring fluid from the reservoir above the piston to beneath the piston for moving the ram.

17. In a hydraulic jack, means constitut-

ing the outer wall of a reservoir, a ram piston within said means and engaging the inner walls thereof, a hollow ram extending into said means and secured to the piston and having an outer diameter such as to provide a space between it and said first 30 means for the fluid supply, a pump plunger operable within said hollow ram and movable with respect thereto and therewith and fitting said hollow ram substantially 35 throughout the length thereof to minimize leakage of fluid between said plunger and ram, and valve mechanism carried by said ram for transferring fluid from the reservoir above the piston to beneath the piston.

18. In a hydraulic jack a movable piston, a ram carried by and movable with said piston, a pump to force fluid under said ram, a plunger included in said pump, two ball check valves to control the flow of fluid under said ram, the two balls of said check 40 valves lying in close proximity and so seated that one ball unseated by said pump plunger will unseat the other ball, thereby relieving both valves.

In testimony whereof I have signed my 45 name to this specification.

FREDERICK R. SUNDERMAN.
